INVENTOR

G. W. McGill

UNITED STATES PATENT OFFICE.

GEORGE W. MCGILL, OF RIVERDALE, NEW YORK.

CHAIN.

SPECIFICATION forming part of Letters Patent No. 351,789, dated November 2, 1886.

Application filed January 19, 1886. Serial No. 189,030. (No model.)

To all whom it may concern:

Be it known that I, GEORGE W. MCGILL, a citizen of the United States, residing at Riverdale, in the city and county of New York, State of New York, have invented an Improvement in Chains, of which the following is a specification, reference being had to the accompanying drawings, forming part of the same, and to the figures and letters of reference marked thereon, in which similar letters of reference indicate corresponding parts.

My invention consists in a chain made from suitable wire, the links of which are made from a single piece of such wire, each link being provided with two loops or eyes, and the ends of the wire forming such links terminating in a spiral twist intermediate or between the two loops in manner to securely lock each loop and to give to the chain the character of a chain made of solid links.

In the drawings, Figure 1 shows a chain so made, the eyes of each link of the chain being oblong in form. Fig. 2 represents the chain similarly made with eyes of round or ring form. In both Figs. 1 and 2 the ends of the wire and the section of its center connecting the eyes are twisted spirally together. Fig. 3 represents the chain having the center section or eye-connecting part of the link-wire left straight and the ends of such wire twisted spirally around it. Fig. 4 represents the ends of the wire forming the links of the chain folded around the straight center or eye connecting part of the same in coils on lines at right angles to the plane of the eyes.

The wire is fed from a reel into a suitable chain-making machine, which automatically cuts off a strip of wire of suitable length and fashions it into a link consisting of the two eyes *a* and *b*, with the ends of the wire terminating in a twist, *c*, around, and in some instances spirally with, the section of wire connecting the eyes, and intermediate therewith. The machine then cuts off a similar piece of wire, one end of which is caused to pass through the eye *b*, and another link is similarly formed, thus connecting both links, and this operation is continued as long as desired.

Fig. 1 represents a chain having the eyes of

its links shaped oblong, and Fig. 2 shaped round.

The ends of the wire of each link may be twisted spirally with the section of wire connecting the loops, as shown in Figs. 1 and 2; or such section of wire may be left straight, as shown by the dotted lines in Figs. 3 and 4, and the ends of the wire twisted around it spirally, as shown in said Fig. 3, or in coils, as shown in Fig. 4.

In locking the ends of the wire in the twist intermediate or between the eyes of the link, I give preference to twisting them from opposite directions from each eye, as shown in Figs. 1 and 2, and in the lower links of Fig. 3, as in this way the two immediate ends of the wire will face each other and make a better finish; but the wire ends may be spirally twisted from each eye, as shown in the top link of Fig. 3, or they may be coiled around the connecting section of the wire, as shown in Fig. 4.

What I claim as my invention, and desire to secure by Letters Patent, is—

1. A chain-link made of a single piece of wire, consisting of the eyes *a b* and the intermediate twisted neck, *c*, as set forth and shown.

2. A chain-link made of a single piece of wire bent to form the eyes *a b*, connected together by the central part of the wire blank, the ends of the wire terminating in a spiral twist around and with the central part of the wire connecting the eyes, as set forth and shown.

3. A chain-link made of a single piece of wire bent to form the eyes *a b*, connected together by the central part of the wire blank, each end of the wire terminating in a coil around the central part of the wire connecting the eyes, as set forth, and shown in Fig. 4.

4. The combination of two or more chain-links, each made of a single piece of wire, consisting of eyes *a b* and the intermediate twisted neck, *c*, to form a chain, as set forth and shown.

In testimony whereof I affix my signature in presence of two witnesses.

GEORGE W. MCGILL.
